UNITED STATES PATENT OFFICE.

JULIUS STEINMEYER, OF ST. LOUIS, MISSOURI.

FERRULE FOR AWL-HANDLES.

SPECIFICATION forming part of Letters Patent No. 233,295, dated October 12, 1880.

Application filed February 26, 1880.

To all whom it may concern:

Be it known that I, JULIUS STEINMEYER, of St. Louis, in the county of St. Louis and State of Missouri, have invented a new and useful Improvement in Ferrules for Awl-Handles, of which the following is a specification.

The object of my invention is to prevent splitting of the awl-handle, to secure both the ferrule and leather pad firmly in place, and to furnish a durable and serviceable awl-handle.

In the accompanying drawings, Figure 1 is an elevation of my improved awl-handle. Fig. 2 is a sectional elevation of the same. Fig. 3 is an end view with the clamping-screw for the awls removed.

Similar letters of reference indicate corresponding parts.

A is the awl-handle. a is the ferrule at the larger or outer end; b, the leather pad; c, the ferrule at the smaller end, and d the screw-ring and clamping device, of usual character for securing awls to the handle.

The ferrule a is formed on the inner surface with a screw-thread, by which it is held securely on the handle, and the pad b is held in the upper end of the ferrule a by the thread. This construction permits ready application and renewal of the pad, and the handle is pre-

vented from being split or battered by use. The ferrule c is also secured in place by the screw-thread formed on its inner surface, so that it cannot come off by the wood shrinking, and this ferrule prevents the lower end of the handle from splitting. I also slot the lower end of the handle, as shown at f in Fig. 3, and the ferrule c being formed with a tapering screw, it will act to clamp the handle upon the shank of the awl and hold the same more steadily than the clamping device d would of itself.

Having thus described my invention, I claim as new and desire to secure by Letters Patent—

1. The awl-handle, screw-threaded at its lower end and provided with slots f, in combination with the screw-threaded ferrule C and the clamping device d, for securing an awl to the handle.

2. In awl-handles, the screw-threaded ferrule a at the outer end, secured upon the handle and carrying the leather pad b, substantially as shown and described.

JULIUS STEINMEYER.
